Primary Examiner — Cynthia R Underwood(74) *Attorney, Agent, or Firm* — Raymond Y. Chan;
David & Raymond Patent Firm(57) **CLAIM**

The ornamental design for a clip hook device, as shown and as described.

DESCRIPTION

FIG. 1 is a perspective view of a clip hook device showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof, showing the clip arm halfly opened; and,

FIG. 9 is another perspective view thereof, showing the clip arm fully opened.

1 Claim, 8 Drawing Sheets(56)
